(57) **CLAIM**

The ornamental design for a faucet body, as shown and described.

DESCRIPTION

FIG. 1 is a front, right perspective view of a faucet body of the new design;

FIG. 2 is a front elevational view of the faucet body of FIG. 1;

FIG. 3 is a rear elevational view of the faucet body of FIG. 1;

FIG. 4 is a left side elevational view of the faucet body of FIG. 1;

FIG. 5 is a right side elevational view of the faucet body of FIG. 1;

FIG. 6 is a top plan view of the faucet body of FIG. 1; and, FIG. 7 is a bottom plan view of the faucet body of FIG. 1. The broken lines are included for the purpose of illustrating portions of the article and form no part of the claimed design.

1 Claim, 5 Drawing Sheets
